UNITED STATES PATENT OFFICE

163,207

STEAM ROLLER TOY

Elmer C. Lennox, Sanger, Calif.

Application October 25, 1949, Serial No. 5,689

Term of patent 14 years

(Cl. D34—15)

To all whom it may concern:

Be it known that I, Elmer C. Lennox, a citizen of the United States, residing at 1416 7th Street, in the city of Sanger, county of Fresno, and State of California, have invented a new, original, and ornamental Design for a Steam Roller Toy, of which the following is a specification, reference being had to the accompanying drawing, forming a part hereof.

Fig. 1 is a perspective view of the steam roller toy, showing my new design;

Fig. 2 is a front elevational view thereof;

Fig. 3 is a side elevational view thereof; and

Fig. 4 is a top plan view thereof.

The handle has been partially broken away in Figs. 3 and 4 for convenience of illustration.

I claim:

The ornamental design for a steam roller toy, as shown and described.

ELMER C. LENNOX.
